UNITED STATES PATENT OFFICE.

CHARLES S. MOON, OF TOPEKA, KANSAS.

CUT-OUT SUSPENSION-PULLEY.

No. 911,252.

Specification of Letters Patent.

Patented Feb. 2, 1909.

Application filed April 13, 1907. Serial No. 367,974.

To all whom it may concern:

Be it known that I, CHARLES S. MOON, a citizen of the United States, residing at Topeka, in the county of Shawnee and State of Kansas, have invented a new and useful Improvement in Cut-Out Suspension-Pulleys, of which the following is a specification.

My invention relates to cut-out suspension pulleys for street lamps, and it is adapted both for electric lamps connected in series and for those connected in multiple.

It comprises essentially two members, one of which is permanently secured to the span wire, and the other of which holds the lamp and is adapted to be raised and lowered and to be clutched by the upper member; the line wires are connected to the upper member, and the parts are so arranged that when the lower member and the lamp are lowered (as for the purpose of cleaning, or repairing, or the like) the lamp will automatically become cut out from the circuit, and the circuit will automatically become closed, or will remain open, according to whether the lamp is connected in series or in multiple.

The invention consists in the special arrangement of the switches; in the special devices for locking the two members together; and in the parts, improvements, and combinations herein set forth and claimed.

In the drawings accompanying and forming part of this specification, and in the description thereof, I have shown my invention in its preferred form and what I deem to be the best mode of applying the principles thereof; but it is to be understood that I contemplate changes in form, proportions, materials, arrangement, the transposition of parts, and the substitution of equivalent members, within the scope of the appended claims, without departing from the spirit of the invention.

Figure 1 is a side elevation of a cut-out suspension pulley made in accordance with the principles of my invention and adapted for a lamp connected in a series circuit; the inclosing hood being shown merely in section. Fig. 2 is a view of one end merely to show the arrangement of the switches. Fig. 3 is a vertical central sectional view of the device, parts being broken away; this view being taken through the line 3'-3', in Figs. 1

and 6. Fig. 4 is a sectional view of the locking device in particular, taken approximately through the line 4' of Fig. 3. Fig. 5 is a sectional view taken approximately through the line 5' of Fig. 4. Fig. 6 is a plan view, the shank of the upper member being shown in cross-section, through the line 6' of Figs. 1 and 3. Figs. 7, 8, and 9 are partial views, similar to Fig. 4, designed particularly to show the operation of the automatic locking device. Fig. 7 shows the lower member entirely disengaged from the upper member; Fig. 8 shows the action of the parts in automatically locking the lower member to the upper member; and Fig. 9 shows the action in automatically unlocking the lower member from the upper member.

Similar reference numerals indicate like or corresponding parts throughout the several views.

Arranged in the upper member 10 is a pulley 11 which travels on the span wire. Another 12 is provided for the drop-cord 23. Holes 13, 13 may be provided above and below the span wire for the guy or brace wires for holding the device in proper erect position; it being understood that the guy or brace wires may be extended in one direction and the line wires in the opposite direction, whereby the suspension pulley is properly held in desired position on the span wire.

14 is a circular plate covering the entire switching and locking apparatus, and on the under side of this plate is a strip of porcelain 15 or other suitable insulator; and from this strip are suspended the two pairs of switch-springs 16, 17 and 16, 17. Preferably the two members of each pair are not arranged exactly opposite each other, but are laterally separated, but each has a lateral arm 18, so arranged that these arms make the contact between the springs. The object of this arrangement is, that if it is desired to use the pulley in a series circuit, these arms may be left as they are shown in the drawings; but if it is desired to use the pulley in a multiple circuit, these arms may be cut off, or bent back; in which latter case no contact will be made when the lower member is withdrawn. A hood 19 may be provided, attached around the rim of the plate 14, to protect the parts from the weather. Depending cen-

trally from the upper member is a shank or plunger 20 having a rib 21 on each side and a hole 22 through the middle for the drop-cord 23.

5 24 may represent the base of the lower member. At each end it is insulated as at 25, and thereon it carries the lower members 26, 27 of the switches. At the lower end of the hollow extension 28 is fitted the cap or stopper 29, held in place by a pin 30, and thereto is secured the end of the drop-cord in any suitable manner, as by knotting its end as shown. Two arms 31, 31 extend downward and carry an insulator 32 on which the lamp 15 may be directly hung. Obviously, therefore, the lamp may be raised and lowered with the lower member by the drop-cord 23; and the object of the devices about to be described is to bring the switches to register, to 20 automatically lock the two members together and to automatically unlock them; all by the operation of the single drop-cord.

Extending up from the base 24 of the lower member is a tube or socket 33 in which 25 the shank or plunger 20 of the upper member fits, and having two slots 34, 34 corresponding to the two ribs 21, 21, of the shank 20. Each of the two parts of the tube or socket 33 is pointed as at 35; and at the lower end of the 30 rib 21 is a roller 36; this arrangement serving to readily guide the ribs into the slots as the lower member is pulled into engagement with the upper member, and thus to bring all the co-acting parts into exact register. 35 At its lower end each rib has a projection 37, whose function will presently be explained. For each rib, slot, and projection, there are a 40 pair of standards 38, 38, arranged as shown in the drawings. Pivoted at 39 between the two standards is a latch 40, having a part 45 thereof cut away as at 41 to allow the clearance of the projection 37 as will hereafter be explained, and having a nose 42 which, when the device is locked rests on the projection 37 and thus holds the lower member to the upper member. The foot of the latch, 43, in this position, engages the end 44 of a tumbler 45, thus preventing the latch from releasing the projection 37.

50 48 is a dog mounted in a lever 46 which is spring-pressed by the spring 47, and this dog normally lies in the path of a lug 49 on the adjacent face of the latch 40. Two corresponding faces of the dog and lug are 55 beveled, and the other two are straight; so that as the latch is swung from position shown in Figs. 1, and 4 toward position shown in Fig. 8, the lug 49 will press back the dog 48 against the tension of the spring 47 60 and will thus pass it; but the dog will not permit the lug to pass in the opposite direction unless the lever be pressed back by other means. The outer face of the projection 37 is recessed as at 50 to correspond to

the inner face of the dog-lever 47, and when 65 the dog-lever so rests in this recess, the dog stands in the path of the lug 49; but when the said lever rests against the projection either above, 51, or below this recess, the dog will be withdrawn from the path of the lug 49, 70 and thus permit it to pass from the position shown in Fig. 8 to the positions shown in the other figures. The latch is so balanced that naturally it tends to the position shown in Fig. 7; and the tumbler 45 is so weighted that 75 it naturally rests in the position shown in Figs. 1, 3, 4, 5, 6, and 7.

A couple of insulators and pins, 60, 60, may be secured to the upper member, as shown, and the line wires attached thereto; 80 the line wires may be led into the hood through suitable weather-proofed openings 61. One wire 70 may be connected to the switch members 16, 16, and the other 71 to the members 17, 17; and the lamp may be 85 connected to the members 26, 26 and 27, 27 respectively, by wires 72 and 73, respectively.

When the lamp is lowered the switches are, of course, disconnected from the lamp, and the circuit is closed or left open according to 90 the presence or absence of the arm 18, as heretofore explained. The latch and tumbler occupy the positions shown in Fig. 7. If, now, the lower member be drawn up, by means of the drop-cord, it will be properly 95 guided into proper engagement with the upper member, as also hereinbefore explained, the projection 37 will first strike against the nose 42 of the latch 40 and force the latch around some distance beyond the dog 48 100 (the passage of the lug 49 by the dog being permitted by reason of the beveled engaging faces), and as the projection 37 clears the nose 42, the latch will by the force of gravity return in the direction of the position shown 105 in Fig. 7, but will be stopped by reason of the dog engaging the lug 49, in the position shown in Fig. 8. As the lower member is pulled still further up, the projection strikes the tumbler 45 and when the lower member 110 is drawn up as far as it will go, the parts have the positions shown in Fig. 8. Now, on slackening the drop-cord, thus letting the lower member be lowered again slightly, the tumbler 45 assumes its natural position when released from the projection 37; and as the upper part 51 of the projection 37 presses back the dog-lever and the dog, the lug 49 is thus released from the dog and thus permits the latch to swing in the direction of its natural 115 tendency until the foot 43 encounters the end 44 of the tumbler 45; and it is held in this position, with the nose 42 resting on the projection 37, thus holding the lower member locked to the upper member, and relieving the drop-cord of the weight of the lamp. This position is shown in Figs. 1, 3, 4, 5, and 6. 120 To release the lock and lower the lamp,

the operation is as follows, assuming the parts to be in locked position as shown in Figs. 1, 3, 4, 5, and 6: The drop-cord is pulled so as to again raise the lower member to the position shown in Fig. 9, the effect being to tip the tumbler 45; also the latch-foot 43, being released from engagement with the tumbler 45, falls still further in the direction of its natural tendency and strikes against the 10 projection 37 and above the end 44 of the tumbler. In this action, the lug 49 has not passed the dog 48, and hence there is nothing to prevent the latch from going to the position shown in Fig. 7 except that the foot 43 15 strikes against the projection 37. Now, as the drop-cord is let out again, lowering the lower member, the foot 43 passes freely under the projection 37 (not being checked by the tumbler 45 which does not come to its 20 first position until foot 43 has passed its end 44); and the projection 37 is permitted to be cleared from the slot 34 by reason of freely pressing back the nose 42, the cut-away portion 41 allowing ample clearance 25 for the projection to pass out as the lower member is lowered away from the upper member. The lower member may then be dropped to the ground, free from the circuit, as fully hereinbefore explained, and may 30 again be drawn up, locked, held, and unlocked, etc.

In practice, the operation is a simple one. To lock the device, the operator simply pulls the drop-cord to its limit and then lets out a 35 little slack to permit the device to be locked; and to let down the lamp, he simply first pulls the drop-cord slightly, and then lets it out.

A special feature of my invention is that all the working parts of the locking device 40 are mounted in the lower member, thus giving ready access to same for purposes of adjusting, cleaning, repairing, etc., without taking down the part which is secured to the span wire.

45 I claim—

1. In a cut-out suspension pulley, the combination with an upper and a lower member, a drop-cord secured to the lower member and passing over the upper member, of a 50 hook on the upper member, and a latch, a tumbler, and a dog on the lower member for locking said lower member to and unlocking it from the said upper member.

2. In a cut-out suspension pulley, the 55 combination with an upper and a lower member, a drop cord secured to the lower member and passing over the upper member, of a hook on one of said members, and a latch, a tumbler, and a dog on the other member.

60 3. In a cut-out suspension pulley, the combination with an upper member and a lower member, a drop-cord, a hook on the upper member, and a latch, a tumbler, and a dog on the lower member for locking said

lower member to and unlocking it from the 65 said upper member.

4. In a cut-out suspension pulley, the combination with an upper and a lower member, a drop-cord secured to the lower member and passing over the upper member, 70 of a hook depending from the upper member, a latch therefor pivoted to the lower member, a tumbler controlled by the upper member for controlling the latch, and a dog for controlling the latch with relation to the tumbler. 75

5. In a cut-out suspension pulley, the combination with an upper member adapted to be secured to the span-wire and having a hook, a lower member adapted to have the 80 lamp suspended thereto and a drop-cord secured to the lower member and passing over the upper member; of a latch pivoted to the lower member and adapted to engage said hook and lock the lower member to the 85 upper member, a tumbler controlled by the upper member to control the latch, and a dog controlled by the upper member to control the latch with reference to the tumbler.

6. In a cut-out suspension pulley, the 90 combination of an upper member having a depending spindle with lugs and hooks on opposite sides thereof, a drop-cord, a lower member having a slotted tube to engage said spindle, and a latch, a tumbler, and a dog 95 mounted on the lower member for each of said hooks and adapted to lock said members together and to unlock them by the manipulation of said drop-cord.

7. In a cut-out suspension pulley, the 100 combination of an upper member and a lower member, a drop-cord, a spindle depending from said upper member and having on opposite sides a hook and a lug, and said lower member having a slotted opening corresponding to said spindle; and a latch, a 105 tumbler, and a dog for each hook and mounted on said lower member.

8. In a cut-out suspension pulley, the combination with an upper and a lower 110 member, a drop-cord, of a hook depending from the upper member, a latch pivoted in the lower member, a tumbler pivoted in the lower member and operated by said upper member for controlling the latch with relation to the hook, and a dog operated by said upper member for controlling the latch with relation to the tumbler. 115

9. In a cut-out suspension pulley, the combination with an upper member having a 120 depending spindle with lugs and hooks on opposite sides thereof and an opening through the center thereof; a drop-cord; a lower member having a slotted tube to engage said spindle, the segments of said tube 125 being each pointed to guide said lugs and hooks into said slots, said lower member being secured to said drop-cord; a device

mounted on the lower member for engaging each hook and comprising a latch to engage said hook, a tumbler controlled by the upper member to lock and unlock the latch, and a dog controlled by the upper member to control the latch with reference to the tumbler; all substantially as set forth.

In testimony whereof I have hereunto set my hand in the presence of subscribing witnesses.

CHARLES S. MOON.
